UNITED STATES PATENT OFFICE

2,453,773

DIPLEX TRANSMISSION BY COMBINED FREQUENCY-AMPLITUDE MODULATION

Charles J. Young, Princeton, N. J., assignor to Radio Corporation of America, a corporation of Delaware

Application November 29, 1943, Serial No. 512,175

2 Claims. (Cl. 178—5.6)

1

The present invention relates to combined signalling systems and more particularly to a system in which sets of intelligence signals, each of a different kind, are transmitted concurrently.

In accordance with the present invention, facsimile signals representing a picture, object, message, or other subject matter are transmitted concurrently with signals which are to be applied to the control and operation of a printing telegraph receiver. The facsimile signals and the printer signals are transmitted together without interference with each other and are recorded separately. The principal sets of signals, namely the facsimile signals and the printer and printer control signals, may be transmitted over a land line, cable pair, or radio link.

This result of non-interfering transmission, reception, and recording is accomplished in accordance with the present invention by amplitude modulating a carrier with one set of signals and frequency modulating the same carrier at appropriate times with the other set of signals. Preferably, the facsimile signals appear as frequency modulations of the carrier, and the printer signals appear as amplitude modulations of the carrier. In this manner a method of modulation well suited to impressing intelligence of each kind on the carrier and to separate intelligence of both kinds from the carrier is employed.

The principal object of the present invention is to provide a method of and apparatus for transmitting facsimile and selector signals simultaneously on a single carrier wave.

Another object of the present invention is to transmit facsimile signals and printer signals simultaneously on a single carrier wave by frequency modulating the carrier wave with the facsimile signals and amplitude modulating the carrier wave with the printer signals.

Other objects of the invention will become apparent when the following specification and claims are read in connection with the accompanying drawings, wherein:

Fig. 1 is a diagrammatic representation of a transmitting station of a communication system embodying the present invention;

Fig. 2 is a diagrammatic representation of a receiving station of a communication system embodying the present invention; and

Fig. 3 shows, by way of example, control circuits and printer operating circuits suitable for use with the invention.

Referring to Fig. 1 of the drawings, there is shown a facsimile scanner and modulator 10 which may comprise a scanner of any type, for

2

example, like that shown on page 80 of Volume I of a book entitled "Radio Facsimile" published in October, 1938, by RCA Institutes Press, New York, New York.

5 A scanner of this type, which has been in general use, provides an output from a photocell or the like representing tones or shades of the subject matter to be transmitted. This scanner output is used to frequency modulate a carrier wave, for example, in the manner shown and described in a patent to Artzt, 2,321,269, granted June 8, 1943. A modulator of the type shown in this patent may be employed in the facsimile scanner and modulator 10.

10 15 The output from the modulator and scanner 10 is indicated graphically by curve 14 and is seen to comprise a wave, the frequency of which is varied in accordance with the light and dark areas of the subject matter which is being scanned for transmission. The frequency of the wave 14 may, for example, vary from 3,000 cycles, when white is being scanned to 4,000 cycles, when black is being scanned. The wave 14 represents the modulated wave 14 with additional signals applied in a manner to be later described. The output from the modulator and scanner 10 with the additional signals may be supplied to a modulator and radio transmitter or carrier current transmitter 16.

20 30 In place of employing the modulator and transmitter 16, the wave 17 may be transmitted directly over a carrier channel by connecting the wire pair of the carrier channel to terminals 18 at the transmitter and to terminals 19 (Fig. 2) at any receiver. Communication may be had with other and perhaps more distant receivers at the same time by employing the modulator and transmitter 16 and the carrier or radio receiver of Fig. 2. The output from the receiver 20 is supplied to a facsimile receiver and recorder 22 which

35 40 may be of any suitable type or design. The output of the carrier current or radio receiver 20 is indicated at 23 and is substantially a replica of the wave 17. The facsimile receiver and recorder 22 may be of any desired type and include any desired recording apparatus. This equipment

45 50 may be arranged as shown and described in detail in a patent to Koch, 2,319,129, granted May 11, 1943. A limiter is preferably included so that a relatively small portion of the amplitude of the wave 23 operates the facsimile recorder. Demodulation of the wave 23 may be obtained by a discriminator, a demodulation filter, or any known

55 means. The output from the demodulator may be employed in the manner shown and described

in the Koch patent just referred to or a chemical recorder may be used.

The facsimile transmitting scanner and recorder may be synchronized in any known manner, for example, by the transmission of a synchronizing signal. Phasing or framing of the recorded copy may also be obtained in any known manner such as by transmitting a special phasing or framing signal. Synchronizing and phasing may be done by varying the frequency of the carrier 14 in the intervals between the printed parts of the scanning lines.

The subcarrier frequency modulated facsimile system just described is operated so that representations of pictures or any other desired subject matter may be sent from the facsimile scanner and modulator 10 to the recorder comprised in the facsimile receiver and recorder 22. Details of the operation of the facsimile system need not be reviewed as it is not part of the present invention. Application of the additional signals to the wave 14 will now be described in detail.

Reference character 26 indicates a keyboard sender or tape sender of any known type which generates five-unit selector signals suitable for operating a selective device such as a telegraph printer. The sender 26 may be of the kind disclosed in a patent to Morton et al., 1,735,633, granted February 4, 1930, or it may be a complete keyboard and printer such as is shown in a patent to Noxon et al., 2,231,215, granted February 11, 1941. If the arrangement shown in the Noxon patent is used, a local printed record may be obtained on the type bar printer which is associated with the keyboard sender.

The sender 26 is shown as comprising a set of "rest" pulse contacts 28 and a series of five intelligence pulse contacts 29. When the sender 26 is in the standby condition, the contacts 28 are closed so that a line relay 32 is energized from a convenient power source, indicated as a battery 33. The relay circuit, which includes the sender 26, also includes a hand operated key 36 which is useful for signalling and may be conveniently employed in a manner to be described to start a printer at a remote receiving station or stations.

Amplitude modulation of the wave 14 with signal combinations set up by the code contacts 29 is accomplished by the tongue and break contact 38 of the relay 32 which bridges a resistor 42 across the output of the facsimile scanner and modulator 10. Resistors 43 and 44 along with the resistor 42 function as a pad so that, during operation of the line relay 32, the impedance reflected into the scanner and the transmitter will not be much changed and frequency distortion will be avoided. The effect of the resistor 42 is indicated by the wave 17, the portion of reduced amplitude occurring when the relay 32 is de-energized.

Operation of the relay 32 will produce square pulses, and 30 per cent amplitude modulation of the envelope of the wave 14 has been found to give excellent results in practice. It will be understood, however, that the degree of modulation will be varied depending upon conditions of use of the invention.

At a receiver station, the wave 23, which is a replica of the wave 17, is applied to an amplifier 49, the output of which is connected through a transformer 50 to the anodes 51 and 52 of a full wave amplitude detector 54. A detector load resistor 55 has its negative end connected to the grid 56 of a power tube 58. A con-

denser 57 serves as a detector filter condenser. A relay 62 in the plate circuit of the tube 58 functions as a line relay. With the detector connected as shown, the tube plate current will increase when the carrier amplitude decreases. The variations in current in the relay coil 62 while revised in phase correspond to the current variations in the coil of the line relay 32, and therefore the coil of this relay 62 may be the actuating magnet of a telegraph printer such as a teletype machine. If this suggested simplified arrangement without the automatic control feature to be described is employed, the contact 38 on relay 32 should be a make contact, or the detector connection to the grid 56 should be reversed, since printers of the usual type are idle with line current flowing. The coil of the relay 62 also may be employed as shown to serve as a line relay to operate a signal relay 66 (Fig. 3) which in turn controls energization of the selector magnet 67 of a telegraph printer indicated generally by reference character 68.

It is within the scope of the invention to arrange the apparatus so that the facsimile signal is transmitted as an amplitude modulation and the printer signal as a frequency modulation of the subcarrier.

By the arrangement of apparatus shown in Fig. 3 of the drawings, it is possible to operate the printer 62 automatically from the transmitting station shown on Fig. 1 over a carrier channel or radio link without the necessity of using grounded or composite circuits.

Referring now to Fig. 3 for a detailed description of the control apparatus, the printer 68 may be of the kind shown in Patent No. 2,231,215, above referred to, which comprises a keyboard sender 72, which may be similar in all respects to the sender 26 of Fig. 1, and a printing mechanism 40 (not shown) controlled by the selector magnet 67. A motor 73 drives the selector and printer mechanism. Power to operate this motor is supplied from a suitable source of power 74 under control of a tongue and make contact 76 of a motor control relay 77. When this relay is energized and locked in a manner to be described, the motor 73 will operate to drive the selector mechanism so that current pulses appearing in the magnet 67 will select characters to be printed.

A source of direct current 79 for operating the printer 68 and the relay system to be described including the line relay 62 may comprise an ordinary rectifier and filter and, as shown, it may be left on continuously so that the printer equipment can be started at all times in response to a call from the key 36 of Fig. 1. One terminal of the supply source 79 is grounded as shown, and the other terminal is connected to a conductor 81 which serves as a bus-bar for supplying control current. The operating coil of a slow-to-operate calling relay 82 is connected to the make contact 83 of the line relay 62 over a conductor 84. The other terminal of the relay is connected to the bus-bar 81. The tongue of the relay 62 is grounded.

The make contact 83 of the relay 62 is also connected to the operating coil of the signal relay 66, the other terminal of this relay being connected to the bus-bar 81 of the supply source 79. One terminal of the printer magnet 67 is grounded as shown, and the other terminal is connected through the keyboard transmitter 72 to the make contact 86 of the motor control relay 77. The tongue of this relay associated with the make

contact 86 is connected to the break contact 87 of the signal relay. By this arrangement, when the line relay 62 operates in response to selector signals applied at the sender 26, the tongue of the signal relay 66 will operate in unison and interrupt the circuit of the printer magnet 67. The marking condition for operation of the printer 68 will be an open circuit condition and the spacing condition will be a closed circuit condition. This is the usual arrangement as pointed out above. The relay 66 is shown as being de-energized so that the printer 68 is in its rest or idle condition with spacing current flowing through the selector magnet 67. The slow-to-operate relay 82 will not respond to the selector signals which are current or no-current pulses of short duration. Even if for a given character, all five selector pulses in the conductor 84 are current pulses, still the relay 82 will not respond since the total time for sending a character is a fraction of a second.

The arrangement for automatically starting the printer motor 73 will now be described. A relatively long control pulse may be obtained by depressing the key 36 shown on Fig. 1 which will cause a long pulse to energize the relay 62 of Fig. 2. Energization of the relay 62 for a sufficient time will cause operation of the tongue of the relay 82 and will complete a circuit from the bus-bar 81 by way of the make contact 89 of this relay, a contact stud 90 on a rotary switch 92, and through the operating winding 93 of a relay 96 to ground. Operation of the relay 96 will close the circuit of the motor control relay 77 at the make contact 98 of the relay 96.

The relay 96 is provided with a locking winding 99 which is connected through a third tongue and make contact 102 of the motor control relay 77 to a tongue and make contact 104 of a slow-to-release relay 106. The operating coil of the slow-to-release relay 106 is connected to the make contact 89 of the slow-to-operate relay 82. The circuit of the locking coil 99 of the relay 96 is also connected to the bus-bar 81 through a break contact 108 of the slow-to-operate relay 82. The slow-to-operate relay 106 serves as a guard to maintain the circuit of the locking coil 99 while the tongue of the slow-to-operate relay is returning to its break contact 108.

After operation of the relay 82 upon the occurrence of a prolonged signal pulse and subsequent release of this relay, it will be seen that energization of the motor control relay 77 is maintained since energization of the locking coil 99 of the relay 96 is maintained at the break contact 108 of the relay 82.

The rotary switch 92 referred to previously has a contact brush 111 and a series of contact studs 90 and 91. Alternate contact studs 90 are connected to a conductor 112 which completes the circuit from the make contact 89 of the relay 82 to the operating winding 93 of the relay 96. Upon each energization of the relay 82, the operating coil 116 of the switch 92 is energized which causes the ratchet pawl 118 connected to its core 119 to be retracted against the thrust of a compression spring 120. When the relay 82 releases, the coil 116 is de-energized and the spring 120 forces the pawl 118 to the right as viewed in Fig. 3 of the drawings, turning the ratchet 121 and causing the brush 111 to move to the next succeeding contact stud 91. This provides an arrangement for shutting down the printer 68 in response to a succeeding prolonged

pulse from the transmitter station without again energizing the relay 96.

Assuming that the printer 68 is in operation and that the relays 77 and 96 are energized and the relay 106 is de-energized, the brush 111 will be on one of the contact studs 91 not connected to the conductor 112 since the spring 120 will have turned the ratchet 121 by an angular distance of one notch. When the next prolonged pulse is received which will be a stopping pulse, the slow-to-operate relay 82 will operate, breaking the connection of the locking coil 99 of the relay 96 which has been maintained at the break contact 108. This will interrupt energization of the relay 77, stopping the printer motor 73. Since the brush 111 of the rotary switch 92 is on a blank stud 91, the operating winding 93 of the relay 96 will not be energized. However, the operating winding 116 of the rotary switch 92 will be energized, and when this winding is de-energized, the brush 111 will be stepped to the next contact stud 90 which is connected to the conductor 112 in readiness for starting the printer motor 73 in response to the next prolonged signalling pulse.

In place of the rotary switch 92 a single-pole double-throw switch may be employed having a magnet which operates the switch contact from one position to the other upon succeeding energizations.

Operation of the entire system will now be reviewed. Assuming that the facsimile scanner and modulator 10 is in operation and that the facsimile receiver and recorder 22 are operating over the radio link provided between the transmitter 16 and the receiver 20, printer communication may be initiated without disturbing this facsimile communication circuit by depressing the key 36. The key 36 need not be kept open for a long time interval, since merely depressing the key manually for a brief time will produce a pulse which is longer than the duration of a complete five-unit selector combination. This results in de-energization of the relay 82 which bridges the resistor 42 across the output of the scanner and modulator 10. At the receiving station shown in Fig. 2, this pulse is detected by the detector 54 and the plate current of the tube 58 increases causing energization of the coil of the relay 62. It will be understood that if desired, the connection may be such that the plate current of the tube 58 will decrease upon the occurrence of a pulse, and if this is done, a break contact on the relay 62 may be employed as pointed out above.

Energization of the relay 62 will apply ground to the operating winding of the relay 82 so that current will flow through this relay for a sufficient time to cause it to operate. When this relay operates, the bus-bar 81 will be connected through the tongue and front contact 89 by way of the brush 111, a contact stud 90, and the conductor 112 through the operating winding 93 of the relay 96 to ground. This relay will operate to energize the motor control relay 77 starting the motor 73 and closing the printer operating circuit at the make contact 86. The slow-to-release relay 106 will operate to maintain the locking circuit on the relay 96 through its locking coil 99 until the relay 82 releases and maintains this locking circuit through its break contact 108. Also, upon release of the relay 82, the brush 111 will be stepped to the next stud 91 which is not connected to the conductor 112.

The printer 68 is usually provided with a cam shaft or distributor shaft which would begin to

rotate when the motor 73 starts unless the shaft is held in its rest position by keeping the printer magnet 67 energized. This is accomplished through a make contact 126 on the relay 106 which keeps the printer magnet 67 energized from the bus-bar 8 during the time that the signal relay 66 is energized while the motor starting pulse is being received. This prevents the printing of garbled characters by the printer 68 during the motor starting period. When the relay 106 releases after an interval of time following its de-energization, the circuit from the bus-bar 81 is opened at the make contact 126 but in the meantime it has closed at the make contact 87 of the relay 66.

With the motor 73 operating, code impulses may now be sent from the sender 26. Briefly, if this sender is of the type which operates from a keyboard, when a key lever on the keyboard is depressed, the contacts 28 are first opened, initiating a start pulse indicated by reference character 128 on Fig. 3 of the drawings. The cam shaft (not shown) of the sender 26 operates the code pulse contacts 29 in succession to a marking or spacing position to give successive pulses of the five unit code in a well known manner. These pulses 129, shown in Fig. 3 of the drawings, are numbered 1 to 5. When transmission of these five pulses has been completed, the contacts 28 again close, giving the rest condition 130 which is maintained until the next key lever is depressed or the next operation of the tape sender occurs in the event that a tape sender is employed. These pulses originating in the sender 26 are repeated by the relay 32 and are detected at the receiving station by the detector 54 and are also repeated by the relay 62. The signalling relay 66 also repeats these pulses, and since the printer 68 is or may be of the type which operates upon current interruption, that is as previously explained, marking pulses being no-current pulses, these pulses will appear as indicated by reference character 133 so that the start pulse will correspond to an energization of the relay 66 which produces a current interruption at its make contact 87.

The printer will respond to these signals for as long as the sender 26 may be operated.

When the operator at the sending station of Fig. 1 has completed transmission, he will depress the key 36 thereby providing a pulse similar to the motor control pulse indicated by reference character 133 on Fig. 3 of the drawings. As previously explained, upon occurrence of this pulse, the relay 82 will operate breaking the circuit of the locking winding 99 of the relay 96 and also, the brush 111 will be stepped to the next stud 90 which is connected to the conductor 112.

The printer channel which has been described in detail may be utilized for indicating to an operator at a receiving station that facsimile communication is desired. For example, the facsimile scanner and modulator 10 may be placed in operation to transmit an unmodulated wave 14 which will be received by the detector 54. If now the key 36 is depressed, the printer 68 at the receiving station will be placed in operation. The keyboard sender 26 may be manipulated to apprise the receiving operator that facsimile communication is desired and the operator will then start his facsimile reproducer and receiver 22.

The operator at the transmitting station may then depress the key 36 to stop the printer 68 which is no longer needed and place copy for

transmission in the facsimile scanner and modulator 10.

If this suggested mode of operation is followed, it will be necessary at all receiver stations to keep the carrier current or radio receiver 20 in operation at all times which may be done with slight expense, since such a receiver, being of a simple nature, will operate with expenditure of very little power.

10 The relay 82 may be used to control other apparatus than a printer, and the relay 66 may be used for other purposes than operating a selector of a printer. Other uses for these relays will suggest themselves to those skilled in the art and such other uses come within the scope of the present invention.

15 Various modifications of the system shown and described herein by way of example are possible, without departing from the spirit and scope of the invention described herein, and it is desired that any and all of such modifications be considered within the purview of the present invention defined by the hereinafter appended claims.

20 Having now described the invention, what is claimed as new and desired to have protected by Letters Patent is:

25 1. A control signal receiving system comprising means to recover control signals from a carrier modulated with image signals and control signals, a relay responsive to prolonged signals recovered from the carrier, another relay responsive to prolonged signals and also signals having a shorter time duration, a control circuit connected to the contacts of said first named relay, a control circuit connected to the contacts of said second named relay, said first named control circuit being operative to exercise a control function upon operation of said first named relay, and said second named circuit being operative upon operation 30 of said second named relay to exercise a further control function, and means for preventing functioning of said second named circuit when said first named relay operates initially.

35 2. A facsimile signal receiving system comprising means to recover facsimile image signals, other intelligence signals and control signals from a carrier, a relay responsive to control signals, another relay responsive to control signals and said other intelligence signals, a control circuit connected to the contacts of said first named relay, an intelligence translating circuit connected to the contacts of said second named relay, said control circuit being operative to exercise a control function in response to a control signal, said intelligence translating circuit being operative also in response to control signals, and means for preventing operation of said intelligence translating circuit when said first named relay operates initially.
